CLAIM

The ornamental design for detachable vamp, as shown and described.

DESCRIPTION

FIG. 1 is a top-front-left perspective view of a detachable vamp showing my new design;

FIG. 2 is a bottom-rear-right perspective view thereof;

FIG. 3 is a left-side elevational view thereof;

FIG. 4 is a right-side elevational view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is an exploded top-front-left perspective view of the present invention, wherein the detachable vamp has been separated from an exemplary article of footwear.

FIG. 10 is an exploded bottom-right-rear perspective view of the present invention, wherein the detachable vamp has been separated from an exemplary article of footwear; and, FIG. 11 is a detail view of area 11 in FIG. 1.

The broken lines showing the exemplary article of footwear in FIGS. 1 through 11 are included for the purpose of showing environmental structure that form no part of the

(Continued)

claimed design. The circles shown with broken lines in FIGS. 1 and 11 are for the purpose of showing area of enlargement and form no part of the claimed design.

1 Claim, 11 Drawing Sheets
